GEOLOGICAL SAMPLE TRAYS

William Darakos, 4815 Center Ave., Pittsburgh 13, Pa.
Filed Nov. 15, 1962, Ser. No. 237,890
4 Claims. (Cl. 35—50)

This invention relates to geological sample trays and particularly to a geological sample tray for preparation and microscopic examination of geological specimens. It is common practice in geological examination of mineral specimens and the like to wash them and then inspect them under a microscope to determine color, grain size and other physical characteristics. This practice has in the past required a multiplicity of specimen holders and a sheet of color chips against which comparison of the sample for color might be made.

The present invention provides a geochromatic tray which overcomes all of these problems. I provide an annular tray having an outer peripheral annular wall and an inner annular wall defining a well through the axis of the tray, a plurality of vertical radial ribs dividing said tray into separate sample compartments, said ribs extending above the outer and inner walls, an outer movable ring carrying side by side color comparator strips, said ring being rotatable about the outer wall of the tray. Preferably said ring is mounted on extrusions on the ribs of the annular tray about the outer wall. Preferably the well formed by the inner wall is adapted to receive a cap member carrying supplementary color charts, porosity chart or some similar physical comparison device. The radial ribs are raised above the general level of the inner and outer walls in order to prevent sample contamination during washing of the individual samples. The ribs also extend over the upper edge of these walls to prevent the water from "curling" around the rib into the adjacent compartment. The open center well provides an outlet for free passage of water when washing samples and provides a receptacle for a comparator device.

In the foregoing general description, certain objects, purposes and advantages of this invention have been described. Other objects, advantages and purposes of this invention will be apparent from a consideration of the following description and the accompanying drawings, in which

FIGURE 1 is a top plan view of a geological sample tray according to this invention;

FIGURE 2 is a section on the line II—II of FIGURE 1;

FIGURE 3 is an enlarged fragmentary view of the outer ring support for the sample tray of the invention;

FIGURE 4 is an enlarged fragmentary view of the well cap and support of FIGURE 1; and

FIGURE 5 is an enlarged fragmentary view of a second embodiment of this invention.

Referring to the drawings there is illustrated an annular tray having a bottom 10, an inner wall 11 and an outer wall 12. The interior of the tray is divided into a plurality of compartments by radial ribs 13. Each of the ribs 13 extends above the level of the inner 11 and outer 12 walls and the ends 13a and 13b extend over the top of said walls to clearly delineate the compartments and

2

prevent any carryover from one compartment to another. Samples of minerals, ores or the like 14 are placed in the compartments and may be washed or chemically treated in situ providing the tray is made of a suitable transparent 5 non-reactive resin or plastic material.

The inner wall 11 defines an opening or well 15 through which water may be exhausted during washing. A comparator cap 16 carrying grain size charts 17 or other comparator information is removably inserted into the well 10 15 when the samples 14 are being examined microscopically so as to provide a convenient comparison. Preferably the ends 13a of ribs 13 are notched or provided with a sloping surface to receive cap 16.

The outer ends 13b of ribs 13 are similarly notched or sloped to receive an outer ring 18 carrying radial mineralogical color chart segments 19 on both sides thereof. The ring 18 may be rotated to bring the desired colored segment 19 into juxtaposition with any given sample 14 under study. Preferably the ring 18 is made up of a transparent, acid resistant and heat resistant plastic having the color charts sealed within it.

In FIGURE 5 there is illustrated a second embodiment of the invention. In this embodiment there is provided an annular tray having a bottom 31, an inner wall 32 and an outer wall 33 slightly higher than inner wall 32. The tray is divided into compartments by radial ribs 34 which extend over the inner wall 32 and outer wall 33. A support ring 35 is provided on the outer wall 33 to carry rotatable comparator ring 36 which carries color chart segments 37. A cap 38 is removably carried in notches 39 on ribs 34. The cap 38 carries a comparator chart which may be grain size, color or other like chart.

In the foregoing description there is set out certain preferred embodiments of this invention. It will be understood, however, that this invention may be otherwise embodied within the scope of the following claims.

I claim:

1. A geological sample tray comprising an annular tray having a bottom, an outer peripheral wall and an inner wall defining a well through the axis of the tray, a plurality of vertical radial ribs dividing said tray into watertight compartments, said ribs extending above the outer and inner walls and an outer movable ring carrying side by side comparator segments rotatable about the outer wall of the tray.

2. A geological sample tray as claimed in claim 1 wherein the outer movable ring is slidable on a cut out portion of the ends of the ribs above the outer wall.

3. A geological sample tray as claimed in claim 1 wherein an annular support means surrounds the outer wall of the tray and is fixed thereto, and the outer movable ring is supported by and movable on said support means.

4. A geological sample tray as claimed in claim 1 wherein a removable cap is supported on the inner ends of the radial ribs above the well and said cap carries supplementary comparator indicia.
